UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

WORK MAGAZINE FOR TYPEWRITING MACHINES.

Application filed July 7, 1921. Serial No. 483,083.

This invention relates to an improved work support to be used in connection with continuous billing typewriting machines, one form of which is shown in the patent to 5 Wernery and Smith, No. 1,132,055.

Usually in a machine of this type, typing is effected on a work web comprising several layers or plies, usually having printed forms. Carbon-sheets interleaved between the plies are mounted on a carbon carriage, so as to advance with the web while typing.

When a different set of forms is to be typed, it is necessary to remove the web temporarily from the typewriter, and bring into use a second web with its carbon-sheets. In the patent to Fortin, No. 1,237,319, granted August 21, 1917, there is provided a carbon-holder (on which the carbon-sheets are directly mounted), which is detachable from the carriage of the typewriter, so that the web and its interleaved carbons may retain their relative positions in the carbon-holder when the latter is removed. A second carbon-holder, having its carbon-sheets interleaved with the layers of the second web, may then be attached to the typewriter. It is only necessary to remove one carbon-holder from the typewriter and attach the other carbon-holder thereto, and the second web will be ready to advance with its interleaved carbon-sheets around the platen at the typing operation.

For convenience in handling and interchanging a plurality of webs, this invention provides, in connection with a table upon which the typewriting machine is mounted, a magazine comprising a plurality of adjacent tiers of containers, each container or compartment having positioned therein a web pack and its attached carbon-holder (when the latter is out of use). The magazine is movably mounted so that any of said tiers may be brought into effective position to deliver to the machine, said position being preferably directly to the rear of the machine. When a tier has been so positioned, the web from any of the containers comprising said tier may be fed to the machine. Each container has an open end to permit the unobstructed withdrawal of the web from the pack in that container. To prevent interference by an upper container of a tier with the web from a lower container in that tier, the containers may be arranged

with their open ends projecting progressively outwardly from top to bottom. The magazine may conveniently be mounted upon the typewriter stand or support, and, where compactness is desired, the magazine 60 may be mounted within the limits of the support. However, when the magazine comprises a large number of tiers, or where the space within the limits of the support is small, it may be necessary to mount the 65 magazine outside of the support.

Other features and advantages will hereinafter appear.

In the accompanying drawings,

Figure 1 is a rear view of the magazine 70 mounted upon a stand or support within the limits of said support.

Figure 2 is a side view, partly sectioned, of the device shown in Figure 1, and showing a continuous billing typewriting machine 75 mounted upon the support.

Figure 3 is a side view partly sectioned, and showing a magazine mounted outside the limits of the stand or support, a continuous billing machine being mounted upon 80 said support.

Figure 4 is a plan view of the device shown in Figure 3.

A stand or support 10 comprises standards 11 and a top 12 which serves as a table for an Underwood continuous billing typewriting machine. This machine comprises a main frame 15 and a rearward extension 16, upon which extension travels a carriage 17, forming part of the paper-carriage. A web, 90 comprising a number of layers of work-sheets, is drawn over a rear guide-rail 18 and is led over a carbon-holder 20, mounted on the carriage 17, the plies of work-web being interleaved with carbon-sheets carried by 95 said holder. The web and interleaved carbon-sheets are drawn forwardly around the platen 21 of the machine and past the printing point, indicated by the type-head 22. The carbon-carriage and web are drawn forwardly as a form is typed on the web, and then the carbon-carriage is returned to its rearward position to co-operate with a new portion of the web, and the typed form is 100 cut off. The process is then repeated to 105 type another set of similar forms.

However, when it is desired to type different forms, another web must be inserted in the machine in place of the previous web. The first web must then be withdrawn from 110

the machine and the new web drawn over the carbon-holder 20 and interleaved with the carbon-sheets before the new forms may be drawn around the platen to typing position. There is provided a carbon-carriage of the form disclosed in the patent to Fortin, hereinbefore mentioned, wherein the carbon-holder 20 is detachable from the body of the carbon-carriage. By providing a plurality 10 of carbon-holders, one for each web, it is merely necessary to change the carbon-holders when it is desired to use a new form, the carbon-holders having previously been attached to their respective webs.

15 In the drawings, the plies of a web, such as 25, are interleaved with carbon-sheets attached to carbon-holder 20, while webs 26 and 27, having different printed forms repeated thereon, have their sheets interleaved 20 with the carbon-sheets attached to carbon-holders 28 and 29. In each case, therefore, the sheets of the web are in adjusted positions relative to the carbon-sheets of their respective carbon-holders, and, when it is 25 desired to substitute web 26, for instance, in place of web 25, it is only necessary to detach carbon-holder 20 and to attach carbon-holder 28, and the sheets of web 26, with its interleaved carbon-sheets, may be drawn forwardly around the platen without further adjustment between the layers of web 26 and the interleaved carbon-sheets.

To facilitate the interchange of webs on the machine, there is provided a magazine 40, having side-walls 41 and subdivided vertically by intermediate partitions 42, each vertical sub-division being sub-divided transversely by cross-members 43 to form containers, so that the vertical sub-divisions 40 form tiers of containers 44 and 45. Each container is bounded by a side-wall 41, a partition 42, the cross-member or base 43, and a front wall 46, the rear being open to permit withdrawal of the webs, one of which 45 is positioned in each container, together with its attached carbon-holder when the latter is not in use. The containers are inclined slightly downwardly at the front, so that the upper layers of the webs can be drawn off without disturbing the lower layers. Each container is located some distance farther rearwardly than the container next above it, thus enabling the webs in the lower containers to clear the upper containers more 55 easily. The bases 43 of the containers are provided with beads 43^a for engaging the webs fed from the lower containers with the least possible friction.

60 To permit proper feeding, it is essential that the container from which the web is fed to the machine should be positioned in effective feeding position directly to the rear of the machine, for, if it is positioned to one side, the web will be twisted when it is withdrawn from the pack. To bring any

desired container, and hence any tier comprising said container, into effective feeding position, the magazine is mounted for lateral movement relative to the support and the machine. In Figures 1 and 2, the magazine 70 is mounted on the support below the top 12 and between the side standards, so that it fits substantially within the limits of the support. The mounting of the magazine comprises a lower rail 50 and an upper rail 75 51 fixed to the support, said magazine having rollers 52 fixed thereto, for running upon the rail 50 and supporting the magazine thereon, and pairs of rollers 53 fixed to the magazine, each pair engaging opposite sides of rail 51 to guide the magazine in its movement. The magazine is so mounted that the open ends of the container face rearwardly, in which position they are nearer the rear of the machine, thus permitting the webs to be fed to the machine more easily. To bring the containers of any tier into feeding position, it is only necessary to move the magazine along the rails.

It will be understood that any number of tiers may be employed, the number in this form of the invention being limited, however, by the distance between the side standards of the support. Thus, for the support shown in Figures 1 and 2, there is sufficient space to allow two tiers to move laterally into and out of feeding position.

Where the space between the standards is used for desk drawers, or where the space is limited and it is desired to employ a large number of tiers, the magazine may be mounted outside the limits of the support. Thus, in Figures 3 and 4, a magazine 60, similar to magazine 40, having a base 61, is mounted by rollers 62 upon rails 63 fixed to a base 64, said base being positioned outside of the limits of the support and to the rear thereof. The base 64 may be provided with openings 65 into which fit the rear standards 11 of the support to prevent movement of the base and fix the relative position of the base and support. It will be obvious that base 64 may be of any length to accommodate a magazine of any number of tiers. The open ends of the containers in the magazine 60 are positioned forwardly, in which position they are nearer to the rear of the machine and can be fed thereto more easily. To permit the upper layers of a pack of web to be withdrawn without disturbing the lower layers, the containers are tilted downwardly at the rear, and each container projects forwardly beyond the edge of the base of the container above it to permit the web from a lower container to clear the container above it more easily.

In operation, it is only necessary to move the magazine along the rails until the tier comprising the desired container is in feeding position, and the carbon-holder and the

desired web attached thereto may then be mounted on the machine. When the web in use is to be replaced by a second web, it is withdrawn from the machine, together with its carbon-holder, and deposited in its container. A second web, with its carbon-holder, is then mounted on the machine, the magazine having previously been shifted along the rails if the container of the second web is in a different tier than the container of the first web. The containers are of a width sufficient to allow lateral play of the webs as the typewriter carriage moves between extreme right and left positions and carries the webs with it. It will be seen that the magazine 60 in Figures 3 and 4 is provided with three tiers of containers, and that the magazine extends beyond the limits of the support or desk 10.

Variations may be resorted to within the scope of the invention, and portions of the improvements may be used without others.

Having thus described my invention, I claim:

1. In combination, a typewriter table, and a magazine for supplying manifold webs to a typewriter on the table comprising a set of web-containers arranged in tiers, said magazine being mounted on the typewriter table for movement laterally thereof to bring any one of the tiers of containers into web-feeding position to enable webs to be fed to the typewriter from any container in said tier.

2. In combination, a typewriter table, and a magazine for supplying manifold webs to a typewriter on the table comprising a set of web-containers arranged in tiers, said magazine being mounted for movement laterally of the table to bring any one of the tiers of containers into web-feeding position to enable webs to be fed to the typewriter from any container in said tier.

3. In combination, a typewriter table, a plurality of tiers of containers for feeding manifold webs to a typewriter on the table, and means on the table for supporting said tiers of containers in different positions laterally of the table, to permit selective positioning of the tiers in web-feeding relationship to the typewriter.

4. In combination, a typewriter table, a set of web-receptacles for supplying webs of different styles to a typewriter on the table, and a support on which the receptacles are fixedly mounted, said support being mounted for movement laterally of the table to bring a selected receptacle into web-feeding position.

5. In combination, a typewriter table, a set of web-receptacles for supplying webs of different styles to a typewriter on the table, and a support on which the receptacles are fixedly mounted, said receptacles being arranged in tiers and banks

and being open at one end, the banks from top to bottom being arranged to have their open ends project progressively outward, the receptacle-support being mounted for movement laterally of the table to bring any tier of receptacles into web-feeding relationship to the typewriter.

6. In combination, a support for a typewriting machine for typing on continuous webs of different styles, and means to facilitate the interchange of said webs in the machine comprising a magazine having a plurality of adjacent tiers of containers, each container for holding a pack of webs and a carbon-holding frame to maintain carbon-sheets interleaved between said webs, said support including rails, said magazine being mounted on the rails and movable along them to bring any of said tiers into effective feeding position relative to the machine, so that the web from any container in the tier in effective feeding position may be fed to the machine.

7. In combination, a support for a typewriting machine for typing on continuous webs, and means to facilitate the interchange of carbon-holding frames and their associate webs in the machine comprising a magazine having a plurality of adjacent tiers of containers, each container for holding a pack of webs and a carbon-holding frame co-operating with the webs, said support including a supporting rail and a guide-rail positioned on said support to extend laterally thereof, said magazine having a roller operating on said supporting rail, and guide-rollers co-operating with said guide-rail to support and guide said magazine for movement laterally of the machine to bring any of said tiers into effective feeding position relative to the machine, so that the web from any container of the tier in effective feeding position may be fed to the machine.

8. In combination, a support for a typewriting machine for typing on continuous webs, and means to facilitate the interchange of carbon-holding frames and their associate webs in the machine comprising a magazine having a plurality of adjacent tiers of containers, each container for holding a pack of webs and a carbon-holding frame co-operating with the webs, said magazine being mounted upon said support and movable within the limits thereof to bring any of said tiers into effective feeding position relative to said machine, so that the web from any container in the tier in effective feeding position may be fed to the machine.

9. In combination, a support for a typewriting machine for typing on continuous webs, and means to facilitate the interchange of carbon-holding frames and their associate webs in the machine comprising a magazine having a plurality of adjacent tiers of containers, each container for hold-

- ing a pack of webs and a carbon-holding frame co-operating with the webs, said magazine being movably mounted on said support and movable within the limits thereof to bring any of said tiers into effective feeding position relative to said machine, so that the web from any container in the tier in effective feeding position may be fed to the machine, said containers each having an open end at the front thereof to permit withdrawal of the webs, the open ends of the containers in each tier being positioned progressively forward from top to bottom.
10. an open end at the rear thereof to permit withdrawal of the webs, the open ends of the containers in each tier being positioned progressively farther rearward from top to bottom.
15. 10. In combination, a support for a type-writing machine of the continuous billing type, and means to facilitate the interchange of carbon-holding frames and their associate webs in the machine, comprising a magazine having a plurality of adjacent tiers of containers, said magazine being mounted to the rear of the support for lateral movement relative to said machine to bring any of said tiers into effective feeding position relative to said machine, so that the 25 web in any container of the tier in effective feeding position may be fed to the machine, said containers each having an open end at the front thereof to permit withdrawal of the webs, the open ends of the 30 containers in each tier being positioned progressively forward from top to bottom.
11. A device to present in effective relation with a typewriting machine a plurality of sheet frames, interchangeable in the machine, for carrying carbon-sheets interleaved with manifold webs; said device including a magazine comprising a plurality of web-containers, and means for mounting said magazine for movement horizontally in the 35 direction of its own length along the rear line of the type-writing machine to bring any one of the containers to effective position relative to the writing operation position of the machine.

JOHN WALDHEIM.
